UNITED STATES PATENT OFFICE.

GUSTAF D. SUNDSTRAND, OF ROCKFORD, ILLINOIS, ASSIGNOR TO ROCKFORD TOOL COMPANY, OF ROCKFORD, ILLINOIS, A CORPORATION OF ILLINOIS.

INDEXING MECHANISM.

1,425,716.

Specification of Letters Patent. Patented Aug. 15, 1922.

Original application filed December 1, 1916, Serial No. 134,280. Divided and this application filed June 29, 1917. Serial No. 177,782.

To all whom it may concern:

Be it known that I, GUSTAF DAVID SUNDSTRAND, a citizen of the United States, residing at Rockford, in the county of Winnebago and State of Illinois, have invented 5 certain new and useful Improvements in Indexing Mechanisms, of which the following is a specification.

This invention relates to improvements in 10 indexing mechanism in which the power member is continuously actuated.

Among the objects of the invention are to provide improved means for automatically 15 indexing a work-spindle or the like which is subjected to an oscillatory movement.

In the accompanying drawings, Figure 1 is a side view of a bevel-gear generator in which the preferred embodiment of my invention has been incorporated. Fig. 2 is a 20 front view of the invention. Fig. 3 is a top plan view of my invention and adjacent parts. Figs. 4 and 5 are sectional views taken on dotted lines 4 and 5, respectively, of Fig. 6 showing the parts in different positions. Fig. 6 is an enlarged sectional view taken on line 6—6 of Fig. 3. Figs. 7 and 8 are detail views of parts in different positions. Fig. 9 is a sectional view taken on dotted line 9 of Fig. 6.

This application is a division of my co-pending application Serial No. 134,280, filed December 1, 1916. The machine shown in the last mentioned application comprises a bevel-gear generator but it will be understood, however, that the improvements herein disclosed are not restricted to use with bevel gear generators but, if desired, may be applied to any machine.

In the accompanying drawings I have 40 illustrated my invention as applied to a bevel gear generator in which the cutting means is reciprocated to and fro and at the same time is oscillated. The gear blank α is supported by the spindle 95 and is synchronously oscillated with the cutting means to effect a rolling motion upon each other to generate a tooth space or the adjacent outlines of adjacent teeth. The preferred embodiment of my invention has been attached to the spindle 95 to automatically index the same and the cutter blank α any desired accurate distance.

After a tooth space or groove has been completed in the gear blank α , the spindle

95 is turned with relation to the gear case 55 114 in order to bring another portion of the blank into position to be grooved by the cutting means. The means for thus indexing the gear blank includes the worm 120 (see Fig. 3), and the worm wheel 121. The 60 worm 120 is mounted upon a shaft 122 to which is fixed a change gear 123 (Figs. 1, 2 and 3). The gear 123 meshes with a change gear 124 which is rigid with a gear 125. The latter meshes with a gear 126 65 which is fixed upon a shaft 127. Also fixed upon the shaft 127 is a drum 128 (Figs. 4, 5 and 6) carrying a dog 129 (Figs. 4 and 5). This dog is adapted to be engaged by a ratchet wheel 130 which is rotatably mounted 70 upon the shaft 127 within the drum 128. Fastened to the hub of the ratchet wheel 130 is a spur gear wheel 131 (Fig. 6) that meshes with a pinion 132 fixed upon a shaft 133. The shaft 133 is connected by means of a 75 universal joint 134 (Fig. 3) with a shaft 135 that extends slidably through a gear case 136 which is pivotally supported at 137 in a bracket 138 fixed to the frame 101. Within the gear case 136 is rotatably supported 80 a bevel gear 139 which is splined to the shaft 135, said shaft being freely slidable longitudinally of the gear 139. Within the gear case 136 is a bevel gear 140 that meshes with the bevel gear 139 and is fixed to a shaft 141 85 (Fig. 2). The shaft 141 is axially aligned with the pivot 137 (Fig. 3). To the lower end of the shaft 141 is fixed a bevel gear (not shown) that meshes with a bevel gear 143 (Fig. 1) fixed upon a constantly-rotating shaft 144. The shaft 144 is rotatably supported in the center of the trunnion upon which the frame 101 is pivoted and is driven by any suitable means such as that shown in my co-pending application referred to. The 95 ratchet wheel 130 is therefore constantly rotating. A spring 148 (Fig. 4) acting against a finger 149 fixed with relation to the dog 129 tends to swing the dog into the path of the teeth of the ratchet wheel 130. The dog 100 129 is normally held away from said teeth, as shown in Fig. 5, by means of a hook 150 adapted to engage the finger 149, said hook being fixed to a rock shaft 151.

When the gear-tooth has been cut, the cutting means is returned to its initial position, and then the hook 150 is raised by the tripping shaft 151 to allow the dog 129 to be

engaged by the ratchet wheel 130, thereby causing the shaft 127 to be rotated one or more times and thus causing the spindle 95 to turn through the proper distance to enable 5 the cutting means, upon the next forward movement thereof, to form the next tooth space. The means for raising the hook 150 comprises an arm 152 (Figs. 1 and 3) fixed to the shaft 151 and pivoted to a rod 158. 10 The rod 153 extends slidably through a guide 154 (Figs. 2, 3 and 6) on the gear case 114. The lower end of the rod 158 is pivoted to one arm of a lever 155 (Fig. 2) carried by the gear case, the other arm of said lever 15 15 resting upon a plate 156. The plate 156 is curved upon the arc of a circle concentric with the axis upon which the gear case 114 oscillates, and said plate is of sufficient length so that it is always beneath the lever 20 155. The plate 156 is secured to a rod 157 (Figs. 1 and 2) which is supported for longitudinal movement upon the frame 101. Fixed to the rod 157 is an arm 158 carrying a beveled pin 159. A rod 160 curved upon 25 the arc of a circle concentric with the frame-supporting trunnion is supported upon the frame 101 in the bearings 161 and 162. Intermediate the bearings 161 and 162 the rod 160 has an elongated opening 163 through 30 which extends a guide pin 164 set in the frame 101. Upon the upper end of the rod 160 is a beveled pin 165 adapted upon the upward movement of the rod 160 to pass under and lift the pin 159 and thus lift the 35 plate 156 and the adjacent arm of the lever 155, whereby the shaft 151 is turned to raise the hook 150 out of engagement with the finger 149. The finger 165 is adapted to yield pivotally upon the downward movement 40 of the rod 160 so as to pass the pin 159. A spring 166 normally holds the pin 165 in the position shown in Fig. 1.

The means for raising the rod 160 comprises a lever 167 pivoted at 168 to the machine frame 1. One arm of said lever carries a rod 169 which is slidably mounted in a guide 170 on the machine frame, the upper end of said rod carrying a roller 171 that underlies a collar 172 which is adjustably 45 mounted upon the rod 160. The other arm of the lever 167 carries a rod 173 (Fig. 1) which, in the return movement of the cutters, is engaged, as described in my copending application referred to, and is forced downwardly, the rod 160 being lifted to raise the plate 156 and thus cause the hook 150 to be moved away from the finger 149. A spring 176 (Fig. 4) tends to move the hook 150 downwardly while gravity returns 55 the rods 157 and 160 after lever 167 has been returned to its original position.

The hook 150 is held up out of the orbit of the finger 149 for the required length of time by means of an adjustable device comprising two notched plates 177 and 178

(Figs. 6, 7, 8 and 9). These disks have notches 179 in their peripheries. In the construction herein shown, the disk 177 has seven notches 179, while the disk 178 has four notches. The disks are located side by side and are relatively adjustable so as to bring the desired notches in the disks into register. In Fig. 7, the disks are shown as so adjusted that notches are in register at two diametrically opposite points. In Fig. 75 8 the disks are shown as so adjusted that notches are in register at only one point. The disks may be adjustably secured together in any suitable manner, as by means of a spring plunger 177^a (Fig. 9) carried 80 by the disk 177 and adapted to enter concave notches 177^b in the disk 178. The disk 178 is fixed upon the hub of a spur gear wheel 180 (Fig. 6) which is rotatably mounted upon a stub shaft 181 in the gear casing 85 114. The spur gear 180 meshes with a pinion 182 which is rigid with the shaft 127. A pin 183 on the hook 150 is adapted to ride upon the peripheries of the disks 177 and 178 and drop into two registering notches 90 179 in said disks. In the construction herein illustrated, the ratchet wheel 130 makes four revolutions to one revolution of the disks 177 and 178. Normally the hook 150 is in engagement with the finger 149, and 95 the pin 183 lies in two registering notches in the disks 177 and 178. When the hook 150 is lifted out of engagement with the finger 149, the pin 183 is held up by the peripheries of the disks 177 and 178 until two 100 registering notches in said disks reach said pin, whereupon the hook 150 drops into the path of the finger 149 and thus causes the dog 129 to be disengaged from the ratchet wheel.

To prevent rebound of the drum 128 and consequent vibration of the spindle 95 when the finger 149 strikes the hook 150, I provide a dog 184 (Fig. 5) which is loosely mounted upon the shaft 151 and is yieldingly held in 110 contact with the periphery of the drum 128 by means of a spring 185. Set in the periphery of the drum 128 is a stop pin 186. By the time that the hook 150 has disengaged the dog 129 from the ratchet wheel 130 the 115 stop pin 186 has just passed the locking dog 184. It will be seen that when the parts are in the position shown in Fig. 5, the hook 150 and the finger 149 prevent rotation of the drum 128 in one direction, and the stop pin 186 and the locking dog 184 prevent rotation of the drum in the opposite direction.

When it is desired to change the adjustment of the disks 177 and 178, access is had to said disk through the opening 187 (Figs. 125 3 and 6) in the gear case 114.

While I have herein shown and described in detail the preferred embodiment of my invention and the operation thereof, I would have it understood that I do not intend 130

thereby to limit myself, but will only be limited by the scope of the appended claims.

I claim as my invention:

1. An indexing device having, in combination, a drum member operatively connected to an indexable member; a dog member pivotally carried by said drum, an actuating shaft; a ratchet member operatively connected to said actuating shaft; and means for operatively associating said dog and ratchet members comprising a spring-pressed finger secured to said dog member, a spring-pressed pivotally-mounted hook member secured to said finger and withholding said dog member from the ratchet, rocking means for releasing said hook member, and means for withholding said hook member comprising a plurality of disk members operatively connected to said drum and rotatable thereby, said disk members having a plurality of registering notches, and a pin member carried by said hook member seatable in said registering notches for restoring said engageable hook member.
2. A dog-and-ratchet mechanism having, in combination, a dog pivotally secured to a rotatable member, a ratchet wheel secured to an actuating member, means for operatively associating said dog and said ratchet wheel comprising a finger member rigidly secured to said dog and a spring member engaging said finger member, means for operatively disassociating said dog and said ratchet wheel comprising a spring-pressed pivotally-mounted hook member adapted to engage said finger member, and means for maintaining said hook out of engagement with said finger comprising a plurality of notched disks rotatable by said rotatable member, said disks having a plurality of registering notches, and a pin member carried by said hook member and operatively associated with said disks.
3. An indexing device for a rotatable member having, in combination, actuating means, a ratchet wheel operable by said actuating means, a dog member operatively connected to the rotatable member and adapted to engage said ratchet-wheel whereby the rotatable member will be rotated by said actuating means, means for intermittently actuating said dog member, timing means operatively connected to said rotatable member, and means carried by the last mentioned actuating means engageable by said timing means for determining the duration of said dog and ratchet wheel connection, said timing means being selectively adjustable to vary the duration of said connection.
4. An indexing device for an oscillating member having, in combination, continuously actuated means for advancing said member a fixed arcuate distance, said means including a flexible connection, connecting
- means intermittently and operatively associating said member with said actuating means, means for actuating said connecting means including a slidable member carried by said oscillating member, an arcuate plate transverse to the axis of oscillation and rigid with said slidable member, and slidable means operatively connected to said arcuate plate for moving the same for actuating said connecting means.
5. An indexing device for an oscillating member having, in combination, continuously actuated means for advancing said member a fixed arcuate distance, said means including a flexible connection, connecting means intermittently and operatively associating said member with said actuating means, means for actuating said connecting means including a slidable member carried by said oscillating member, an arcuate plate transverse to the arc of oscillation and rigid with said slidable member, and means including a "one-way" actuating device for moving the arcuate plate.
6. An indexing device for an oscillating member having, in combination, continuously actuated means for advancing said member a fixed arcuate distance, connecting means intermittently and operably associating said member with said actuating means, and means for actuating said connecting means including a finger, a rock shaft, an arm fixed thereto, a rod pivoted to the arm, a lever pivoted to the rod, an arcuate plate concentric with the axis upon which the member is oscillated and beneath said plate, said plate being slidably supported by the frame structure upon which the member is oscillatably supported and means for slidably moving the arcuate plate to actuate said lever.
7. An indexing device for an oscillating member having, in combination, continuously actuated means for advancing said member a fixed arcuate distance, connecting means intermittently and operably associating said member with said actuating means, means for actuating said connecting means including a finger, a rock shaft, an arm fixed thereto, a rod pivoted to the arm, a lever pivoted to the rod, an arcuate plate concentric with the axis upon which the member is oscillated and beneath said plate, said plate being slidably supported by the frame structure upon which the member is oscillatably supported and means for slidably moving the arcuate plate to actuate said lever, and spring means for returning said connector-actuating means.
8. An indexing device having, in combination, a shaft to be indexed, a dog member operatively connected thereto, a continuously rotating actuating shaft, a ratchet wheel operatively connected to said operating shaft and engageable by said dog mem-

ber, means involving positive engagement between said indexed shaft and said dog member adapted to limit the movement of said dog member in the direction of release and relatively stationary means adapted to engage and release said dog member from said ratchet, whereby said dog member and relatively stationary means act as a positive stop against further rotation of said indexed member.

9. An indexing device for a shaft having in combination, a rotatable member, continuously actuated means, connecting means between said rotatable member and said actuating means, disconnecting means for disassociating periodically said connecting means from said actuating means, and timing means selectively adjustable to a plurality of settings for determining the interval between the operation of said connecting means and said disconnecting means.

10. An indexing device having, in combination, a shaft to be indexed, a dog member operatively connected thereto, an actuating shaft, a ratchet wheel operatively connected to said actuating shaft and engageable by said dog member, means in the nature of a shoulder on the shaft to be indexed adapted to engage and limit the motion of said dog in the direction of release, relatively stationary means adapted to engage said dog and move it against said shoulder whereby said dog and said relatively stationary means act as a positive stop against further rotation of said indexed member, and additional means for preventing recoil of said indexed shaft in the opposite direction.

11. An indexable device having, in combination, a rotatable member, continuously actuated mechanism, and means for intermittently and operatively connecting said member with said mechanism comprising a controlling device operatively connected with said rotatable member for timing the operation of the connecting means, said controlling device being adjustable to vary the timing of the operation of the connecting means.

12. In an indexing device, a rotatable member, a continuously operating actuating mechanism, a device adapted to connect said members for rotation together, and mechanism for intermittently operating said device to disconnect said members, said mechanism including a pivoted part and a rotatable element comprising a pair of relatively adjustable disks having notches in their peripheries certain of which are arranged

to register so as to be capable of receiving said part.

13. In an indexing device having a part to be intermittently operated, timing mechanism comprising a pair of disks rotatable as a unit and having a plurality of peripheral notches, said disks being angularly adjustable with respect to each other whereby certain of said notches in the disks may be caused to register, and a reciprocating member movable, when the registering notches of said disks are disposed in the path of movement of said member, into operative engagement with the part to be operated.

14. An indexable device having, in combination, a rotatable member, continuously actuated mechanism, and means for intermittently connecting said member with said mechanism comprising hook means carried by said member and normally tending to connect said member with said mechanism, a second hook means adapted to engage said first-mentioned hook means and hold the same in inoperative position, means for intermittently withdrawing said second mentioned hook means, and automatic means for holding said second mentioned hook means in withdrawn position during a predetermined motion of said rotatable member, said means being adjustable to vary the amount of motion of said member resulting from each actuation of said second mentioned hook means.

15. An indexable device having, in combination, a rotatable member, continuously actuated mechanism, and means for intermittently connecting said member with said mechanism comprising hook means carried by said member and normally tending to connect said member with said mechanism, a second hook means adapted to engage said first-mentioned hook and hold the same in inoperative position, means for intermittently withdrawing said second mentioned hook means, and automatic means associated with and driven from said rotatable member for holding said second mentioned hook means in withdrawn position during a predetermined motion of said rotatable member, said means being adjustable to vary the amount of motion of said member resulting from each actuation of said second mentioned hook means.

In testimony whereof, I have hereunto set my hand.

GUSTAF D. SUNDSTRAND.
